R. C. MUNRO.
CARLINE.
APPLICATION FILED NOV. 5, 1919.

1,378,051.

Patented May 17, 1921.

UNITED STATES PATENT OFFICE.

ROY C. MUNRO, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CARLINE.

1,378,051.

Specification of Letters Patent.

Patented May 17, 1921.

Application filed November 5, 1919. Serial No. 335,923.

To all whom it may concern:

Be it known that I, Roy C. MUNRO, a citizen of the United States, residing in Chicago, in the county of Cook and State of Illinois, have invented a new and useful Improvement in Carlines, of which the following is a specification.

The invention relates to carlines more particularly designed for use in freight car roof frames, and has for its objects to simplify the construction of the carline and attain economies in manufacture, at the same time producing a carline of great strength and stiffness against vertical and torsional strains.

With such objects in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:—

Figure 1 is a plan view of a portion of a car roof frame suitable for freight cars and other purposes, comprising a carline embodying and illustrating the invention.

Fig. 2 is a side elevation of the carline, showing also, in vertical section on a plane transverse to the roof, the frame and sheathing elements of the structure.

Fig. 3 is a vertical section on a larger scale on line III—III of Fig. 1, showing in elevation one of the end portions of the carline.

Fig. 4 is a horizontal section, looking upward, taken on the plane of the bolt which secures an end of the carline to a side plate, and showing in section a portion of the side plate and a portion of one of the vertical flanges of the carline.

Referring to the drawing, A indicates the carline, 2 the supporting side plates, 3 the

supported ridge pole, 4 the purlins carried by the carlines, 5 the top sheathing, 6 the side sheathing and 7 the side fascia, the invention being illustrated in a freight car structure.

The carline A is constructed of three steel L-bars 8, 9 and 10 riveted together at the apex of the carline and ridge of the roof, and declining thence to both of the side plates, and inclining away from each other longitudinally of the car on opposite diagonals so as to form four widely separated points of attachment to the side plates. Said bars are formed and arranged so as to have horizontal top flanges *a* and vertical side flanges *b*.

The bar 8 is a main through bar spanning the roof from side plate to side plate in a diagonal direction, and at each end said flanges *a* and *b* are split apart, the vertical flanges terminating in feet 11 (Figs. 3 and 4) which are bent parallel with and braced against the inner faces of the side plates, and the horizontal flanges extending across and bearing on the tops of the side plates and terminating in downwardly bent hooks 12 which engage the outer faces of the side plates. The middle part of the bar 8 is formed at the apex of the carline, with a short horizontal portion 13 which carries the ridge pole 3, and preferably the ends of the bar are bent upward relative to the main inclined portions to form parts 14 which extend horizontally outward to and engage the side plates as already described.

The bars 9 and 10 are supplementary to the bar 8 to form a double-Y or double branched carline, and are or may be counterparts of each other in size and formation, whereby their preliminary shaping is a simple matter by a single set of forming devices. Relative to their outer inclined parts 95 the inner ends 15 of said supplementary bars are both bent to the left (as viewed in Fig. 1) to bring them into parallelism with the main bar 8, and are also bent downward so as to be horizontal and parallel with said portion 13 of the main bar. Being thus shaped the supplementary bars are arranged with their ends 15 at either side of the vertical flange *b* of said middle part 13, the three vertical flanges thus brought together 105 being securely united by rivets or bolts 16.

One of said supplementary bars, as the bar 9, may be arranged with the top flange α of its end 15 flush with the similar flange of the bar 8 to form a further bearing for 5 the ridge pole, and receive the securing bolt 19 of the latter. The flange α of the end 15 of the bar 10 is arranged under and in supporting contact with the under side of the flange α of said main bar (Fig. 2). The 10 outer parts of the bars 9 and 10 are inclined away from the main bar on corresponding and opposite diagonals, and their ends are formed for engagement with the side plates as illustrated and as already described with 15 respect to the ends of the bar 8, and said ends are secured by bolts 17 which pass through their feet 11 and through the side plates.

The purlins are secured by bolts 18 which 20 pass through the flanges α of the inclined parts of the bars 8, 9 and 10.

It will be seen from the foregoing that the four ends of the carline branches may be conveniently formed for strong and secure 25 engagement with the side plates without weakening the latter; that the carline is composed of parts which can be simply and economically formed; that the apex of the carline is strongly reinforced so as to form 30 a solid point of resistance to receive the thrusts of the carline branches; and that the carline as a whole is well adapted to durably resist all vertical, horizontal and torsional strains arising from hard usage of the car.

35 What is claimed is—

1. In a carline for car roofs and the like, the combination of a main L-bar arranged with horizontal top flanges and depending side flanges, and having a central apex, declining thence to the side plates and having 40 its ends formed for engagement with the side plates; and supplementary L-bars having laterally bent inner ends arranged at the sides of said apex with the vertical flanges of all of said bars in contact and secured together to form a frame-supporting apex of triple width, and declining 45 thence, and inclining away from said main bar, to the side plates, and having their outer ends formed for engagement with the side plates.

50 2. In a carline for car roofs and the like, the combination of a main L-bar arranged with horizontal top flanges and depending side flanges, and having a horizontal central apex, declining thence to the side plates and having its ends formed for engagement with the side plates; and supplementary L-bars, having laterally bent inner ends arranged 55 at the sides of said apex with the vertical flanges of all of said bars in contact and secured together to form a frame-supporting apex of triple width, and declining thence, and inclining away from said main bar, to

the side plates, and having their outer ends 65 formed for engagement with the side plates.

3. In a carline for car roofs and the like, the combination of a main L-bar arranged with horizontal top flanges and depending side flanges, and having a horizontal central apex, declining thence to the side plates and having its ends formed for engagement with the side plates; and supplementary L-bars, having laterally bent inner ends arranged at 70 the sides of said apex with the vertical flanges of all of said bars in contact and secured together to form a frame-supporting apex of triple width, the horizontal flange of one of said supplementary bars being arranged flush with the top of said apex and the horizontal flange of the other bar being arranged against the under side 75 of the horizontal flange of the main bar, said supplementary bars declining thence, and inclining away from said main bar, to the side plates, and having their outer ends 80 formed for engagement with the side plates.

4. In a carline for car roofs and the like, the combination of a main L-bar arranged with horizontal top flanges and depending side flanges, and having a horizontal central apex, declining thence to the side plates and having its ends formed for engagement with the side plates; and supplementary L-bars, having laterally bent inner ends arranged at 85 the sides of said apex with the vertical flanges of all of said bars in contact and secured together to form a frame-supporting apex of triple width, and declining 90 thence, and inclining away from said main bar, to the side plates, and having their outer ends formed for engagement with the side plates.

95 5. A three-part carline, comprising a main bar extending from eaves to eaves of the roof in a diagonal direction and bent to form a central apex, and two supplementary bars having their inner ends bent into parallelism with and secured to the opposite sides of the middle part of the main bar, and inclining thence away therefrom on diagonals corresponding with and opposite to the diagonal of the main bar and also declining to the eaves, to form a double-branched carline.

100 6. A three-part carline, comprising a main bar extending from eaves to eaves of the roof in a diagonal direction, and two supplementary bars having their inner ends bent into parallelism with and secured to the opposite sides of the middle part of the main bar, and inclining thence away therefrom on diagonals corresponding with and 105

opposite to the diagonal of the main bar and also declining to the eaves, to form a double-branched carline, all of said bars being bent in vertical directions to form a central apex.

5 7. In a carline, the combination of a single member extending from support to support and in a diagonal direction, and two separate members arranged on the opposite

diagonal and braced against the sides of said single member, all of said members 10 being of L-section and having their vertical flanges secured together in parallelism and contact.

In testimony whereof I have hereunto set my hand.

ROY C. MUNRO.
